UNITED STATES PATENT OFFICE.

LAWRENCE A. SUBERS, OF EAST CLEVELAND, OHIO.

LAMINATED, COHESIVE, INTERWOUND FABRIC BAND, BONDED AND TESSELLATED.

1,187,564.

Specification of Letters Patent. Patented June 20, 1916.

Application filed July 10, 1914. Serial No. 350,147.

To all whom it may concern:

Be it known that I, LAWRENCE A. SUBERS, a citizen of the United States, and resident of East Cleveland, in the county of Cuyahoga and State of Ohio, have invented certain new and useful Improvements in Laminated, Cohesive, Interwound Fabric Bands, Bonded and Tessellated, of which I hereby declare the following to be a full, clear, and exact description, such as will enable others skilled in the art to which it appertains to make and use the same.

The invention relates to that type of fabric band which is employed in constructing the Subers laminated, cohesive, interwound fabric, described in Letters Patent granted to him on February 13, 1912, No. 1,017,271 and on March 26, 1912, No. 1,021,014; and is itself constructed in preferably tubular form and from laminated, cohesive, interwound, fibrous elements, in a similar manner and afterward flattened to form a flexible band.

The fabric band is composed of series of fibrous elements laid or wound in parallel, spaced rows, at a predetermined angle, the rows of one series crossed by the rows of other series, said series being laid alternately in opposite directions, and the spaces between the rows of one series being substantially covered by the rows of the next laid parallel series. In this manner spaced openings are produced throughout the fabric before the fabric has been compressed. The tubular structure thus produced is then flattened under pressure and the pressure forces the elements which lie over the spaces into them, until a smooth, laminated structure with selvage edges is produced without openings of any sort.

The present improvement is designed to provide, in addition to the fluid adhesive material with which the fibrous elements are coated as the fabric band is being constructed upon the mandrel, a continuous layer or bands of solid rubber or other suitable adhesive substance interposed between the series of elements described, and which may be of any desired thickness, so that when the

tubular fabric has been compressed to form 50 a band the rubber will cover and enter the previously mentioned spaces or openings and will furnish a surface to which the elements in the series, which cross above and below the openings, will adhere. The several 55 bands when completed will also have the rubber filled spaces exposed at regular intervals upon their outer surfaces, the result being that a series of such bands will adhere more firmly together when interwound 60 with each other to form a fabric. This produces an unwoven but homogeneous fabric of predetermined extensibility and suitable for use in pneumatic tires or casings and for fire and air brake hose or analogous tubing. 65

The invention is illustrated in the accompanying drawings, and is hereinafter more fully described, and specifically pointed out in the claims.

In the accompanying drawings Figure 1 70 is a plan view of a flattened band showing the manner of introducing the rubber therein; Fig. 2 is a transverse section thereof showing the spaces and the rubber in the form of a continuous layer interposed there- 75 in, before the band has been compressed; Fig. 3 is a longitudinal section of the same; Fig. 4 is a transverse section thereof after compression, showing the rubber layer deflected by compression into all of the spaces 80 and filling the same; Fig. 5 is a longitudinal section of the same, and Fig. 6 is a plan view of the completed band taken upon a reduced scale; Fig. 7 is a transverse section 85 of the band before being compressed, showing an additional continuous, solid adhesive band incorporated in the center thereof.

In these views A, A represent the series of parallel spaced fibrous elements which are the first laid as the band is constructed by 90 winding them spirally upon a mandrel at a predetermined angle.

B, B represent a series of spaced fibrous elements laid in the opposite direction, preferably at the same angle thereover. Upon 95 these series is laid a layer composed of bands or strips of unvulcanized rubber C, C, or other adhesive material, and upon the rubber band

are spirally wound series D and E, of fibrous elements corresponding to the series A and B, and respectively parallel thereto and so positioned as to cross and cover all the spaces or openings between the spaced fibrous elements of series A and B. These four series form the fibrous structure of the fabric band.

When the tubular band is flattened, as seen in Figs. 1 and 2, the rubber layer will occur at regular intervals throughout the band in the diamond-shaped spaces C, C, formed between the fibrous elements and giving to the outside of the band a checkered or tessellated appearance.

In Fig. 7 is shown a transverse section of a band before being compressed, in which a center strip of solid adhesive is introduced in addition to the layer of solid adhesive above described, thus offering an additional means of binding the two first laid series of fibrous elements together after the band has been flattened. After the band has been placed under pressure the opposed rubber bands filling the inner openings in the two sides of the fabric, will unite together therethrough and also will unite to the opposite fabric elements and will bind the laminations so closely together that it is difficult to tear them apart, and thus a thoroughly homogeneous product is formed. The band thus constructed has also a predetermined amount of extensibility, depending upon the angle at which the fibrous or yarn elements are interwound and positioned in forming the band. In practice, after the adhesive binding material in the band has become solidified to a certain degree, when the liquids and gases have been evaporated from the fluid adhesive, the band can be stretched and will afterward remain elongated a certain amount, since the band, being of tubular construction, will tend to grow smaller and longer, but owing to its flattened condition and since the layers are held together by the solidified binding material, it will elongate and become slightly narrower without unduly stretching the yarns. When incorporating these bands in a tubular fabric, the extensibility of the latter both in axial and diametrical directions may be governed both by the relative extensibility of the bands in the several layers of the fabric and also by the relative angular positions of the fabric bands in these several layers. The different layers of fabric in a tube constructed in this manner become practically a unit in resisting internal pressure.

It is obvious that a centrally positioned strip of solid adhesive material may be used alone in the construction of the fabric band, in addition to the fluid adhesive with which the several yarns in each series are coated, or a partial or integral layer of adhesive

may be introduced between any of the alternately laid series of fibrous elements as they are being interwound and laminated in constructing the fabric band, without departing from the spirit of the invention or the scope of the claims.

It is obvious that a series of yarns or threads or fibrous elements of any desired material, or bands therefrom, may be used as the fibrous elements in constructing the fabric band. It is also obvious that a multiplicity of series of fibrous elements with or without a multiplicity of interposed layers of solid adhesive material may be used in conjunction with a fluid adhesive substance in constructing a laminated, cohesive fabric band of multiple layers.

Having described the invention, what I claim as new and desire to secure by Letters Patent is:

1. A tubular, compressed fabric band comprising series of parallel, spaced, interwound, fibrous members, one series crossing the adjoining series at an angle to form spaced openings between said members, four of such series being incorporated in the band, and a layer of vulcanizable adhesive interposed between the first two and last two series of said members, said openings being opposite to each other on the inside of the band, and the inner faces of the layer of adhesive cohering together through said openings.

2. A fabric band comprising a series of spirally wound fibrous elements, laid in parallel spaced rows, each element composed of substantially parallel yarns coated with a fluid adhesive, a second series of spaced parallel elements spirally wound thereon in the opposite direction and crossing the said first series at an angle, a layer of solid adhesive laid thereon, a third series of spaced yarn elements wound thereon parallel to said first series and covering the spaces between the elements of said first series, a fourth series wound thereon parallel to said second series and covering the spaces between the elements of the said second series, the said band flattened thereby providing selvage edges, and the opposite sides of the layer of adhesive cohering together through the openings formed between said series of yarn elements.

3. A compressed fabric band composed of laminated, interwound fibrous elements and having spaced openings interposed between said elements, and a continuous band of solidified adhesive material passing between said elements and being deflected to fill said openings when said band is compressed.

4. A compressed fabric band composed of interwound, fibrous elements, and having spaced openings interposed between said elements throughout its substance and appearing upon its surface and a continuous layer

of adhesive material passing between said elements and filling said openings, said layer appearing in the spaced surface openings.

5. A fabric band comprising a flattened tube composed of series of spaced fibrous elements providing spaced interposed openings, a continuous band of adhesive material centrally inserted in said flattened tube, and a continuous layer of adhesive material pass-

ing between the series of spaced yarn elements of said band, and filling said interposed openings.

In testimony whereof, I hereunto set my hand this eighth day of July, 1914.

LAWRENCE A. SUBERS.
